UNITED STATES PATENT OFFICE.

GEORGE A. WHITE AND WILLIAM SPARKS, OF JACKSON, MICHIGAN, ASSIGNEES TO THE SPARKS-WITHINGTON COMPANY, OF JACKSON, MICHIGAN, A CORPORATION OF OHIO.

SIGNALING DEVICE.

Application filed June 13, 1927. Serial No. 198,422.

This invention relates to certain new and useful improvements in signaling device.

The main object of the invention is the production of a novel signaling device particularly designed for use on automobiles and capable of producing a comparatively loud signal that will carry long distances, and is of a musical tone, or a combination of musical tones, preferably of a harmonious character, and the specific features of the invention reside in the particular assemblage and mounting means of a portion of the structure whereby the signaling device is rigidly supported in position with its ornamental sound-emitting portion positioned external of the vehicle body, while the driving means and supporting bracket is, for instance, under the hood of an automobile where it is not ordinarily exposed to view.

Other objects and advantages relate to the details of the structure and the form and relation of the parts thereof, all as will more fully appear from the following description, taken in connection with the accompanying drawings, in which:

Figure 1 is a plan view of the signaling device of this invention, omitting the wall of the vehicle in connection with which the device is assembled.

Figure 2 is a section on line 2—2, Figure 1, with the wall of the vehicle included.

Figure 3 is a plan view similar to Figure 1, but showing portion of the structure in section.

Figure 4 is a section on line 4—4, Figure 1, including the wall of the vehicle body.

Figure 5 is a section on line 5—5, Figure 2.

The structure herein illustrated comprises a rotary electric motor —1— disposed upon the interior of the wall —92— of a vehicle body, while the horn body —91— and projectors —60— are disposed exterior of the wall —92— of the vehicle body to constitute an exposed ornamental structure.

The armature shaft —4— of the motor is journaled in an end wall —2— preferably of substantially circular form, and provided with a central boss —3— constituting an elongated journal for the armature shaft.

The rear end of the armature shaft —4— extends through an opening in the U-shaped case —7— and may be provided with an adjustable bearing —5— carried by the end or cross-wall —6— of the U-shaped motor-case

—7—. The ends of the U-shaped motor case —7— are secured to flanges —8— respectively formed upon the end wall —2—. The usual armature —10—, pole pieces and field coils —11— are provided.

The actual structure of the motor may vary widely, the essential being a means for producing rotary movement, and any form of electric motor may be utilized which is capable of driving a rotary compressor which constitutes a portion of the device, and for this purpose the end wall or head —2— is formed with a circular chamber or cylinder —14— in the side of the head opposite the electric motor —1—, and this cylindrical recess or chamber is eccentric with respect to the armature shaft —4— and to the rotor shaft —15— which is aligned with the armature shaft —4— and the rotor shaft may be connected to the rotor —13— in any suitable manner, as for instance formed integrally with the rotor.

The rotor shaft extends into and is journaled in the boss —3— and may terminate a short distance from the end of the armature shaft —4— and is connected to the armature shaft for simultaneous rotary movement, while permitting relative longitudinal movement in any suitable manner, as by a key —50— extending into slots formed in the adjacent ends of the rotor shaft and the armature shaft for locking the two against relative rotary movement, the key being positioned at an intermediate point along the bearing —3—.

In effect the armature shaft —4— and the rotor shaft —3— constitute a sectional armature shaft and for the purpose of the claims of this application may be so considered.

The armature shaft being concentric with the end head —2— and the rotor —13— being concentric with the armature shaft, the circular rotor is eccentrically positioned in the cylinder or chamber —14— by reason of the fact that the cylinder is formed eccentrically in the end head.

The end head —2— is further formed with an air storage chamber —17—, in this instance arranged concentrically with the wall of the cylindrical chamber —14— and extending around the cylindrical chamber throughout slightly more than one-half of its circumference. This storage chamber is in communication with the pressure side of the rotary pump through a port —18— in the wall

of the chamber —14—, and through this port air under pressure is projected by the rotor —13— from the chamber —14— and for effecting this result the rotor —13— includes 5 one or more, in this instance three movable blades —19— slidably mounted in grooves or recesses in the rotor, and preferably spaced equal distances apart and adapted to be thrown out by centrifugal force as the rotor 10 —12— is driven by the armature shaft.

The compressor chamber —14— is formed with an air inlet —20— at the suction side of the compressor, and which air inlet penetrates the bottom wall of the compressor 15 chamber, and leads into the casing —51— which encloses the electric motor —1—. This casing is usually imperforate, and for the purpose of admitting air to its interior, it is formed with a struck-up portion —52— in- 20 terrupting the continuity of the casing wall, and forming a passageway —53— leading to a passageway —54— through the flange —55— on the end head —2—, whereby air may be freely supplied to the inlet —20— 25 of the compressor and without the production of vacuum within the casing —51—.

Mounted upon the outer end of the head —2— and covering the compressor chamber —14— and the storage chamber —17— is an 30 end cap —80— secured to the head —2— in any suitable manner, as by screws —81—. This end cap is formed with a boss —82— provided with a conduit —95— leading to the storage chamber —17— and the outer end 35 of the conduit —95— is interiorly threaded for the reception of the threaded end of a swivel connection —100—, the opposite enlarged conical end of which is secured to and in alignment with a threaded nipple 40 —89— by means of cap-nut —101—. The nipple —89— has mounted thereon a threaded nut —102— inside the wall —92— and the nut is spaced from the wall —92— by one arm —103— of a supporting bracket —104— 45 and the nipple —89— extends through the arm —103— of the bracket and through an opening in the wall —92— and is threaded into an opening in the base of the horn body —91—.

50 Preferably, the horn body —91— may be spaced from wall —92— by washer —105—. When this association of the elements has been made, the nut —102— may be tightened against the arm —103— of bracket —104— 55 to rigidly secure the parts in position and connect the same rigidly to the wall —92—.

The other arm —106— of bracket —104— is connected to the end head —2— by means of bolts —107— two of which are shown ex- 60 tending through the arm —106— and threaded into recesses in the end head —2— to constitute a substantial support for the motor and compressor.

The structure here illustrated is designed 65 to include two sound producing structures,

and except for the length of the projectors —60—, these sound producing devices are of similar form, shape and structure, and a description of one constitutes a description of both. The projectors —60— differ in this 70 illustration in that one of them is somewhat longer than the other for the purpose of producing different notes, which by suitable adjustment of the devices can be made harmonious in character.

In each case the projector —60— has its rear end threaded into the front end of one of the bosses —59— on the horn body and a tube —61— is threaded into the boss so as to substantially contact with the rear end of the projector —60—, and this tube projects rearwardly from the boss —59—.

Each boss —59— has a circumferentially enlarged intermediate portion forming an annular chamber —62— surrounding the tube —61— and in communication with the respective conduits —58—. The rear end of each boss is internally enlarged with respect to the front end and is threaded for the reception of an externally threaded tubular boss 90 —63— formed concentrically at the base of a cup-shaped member —64— which may be locked in any desired position with respect to boss —59— by means of lock-nut —65—.

The internal diameter of the boss —63— 95 is somewhat greater than the external diameter of the tube —61— so as to form an annular passageway around the tube leading from chamber —62— to the interior of the cup- shape member —64—. The external wall of 100 the cup-shape member —64— is externally threaded for cooperative engagement with the interiorly threaded flange upon a cup- shape cap —66—, and this cap —66— is formed with a radial shoulder —67— between which and the end of the cup-shape member —64— a thin metallic diaphragm —68— has its edge confined.

The size and arrangement of the parts is such that when the diaphragm is positioned, 110 as described, it extends across and normally closes the rear open end of the tube —61— and preferably the rear open end of tube —61— is flared, as indicated at —69—.

It is found that the air in the chamber between the diaphragm —68— and the cap —66— varies in pressure somewhat in accordance with the temperature to which the device is subjected, thereby varying the pressure upon the diaphragm —68— which in 115 turn effects the operation of the signaling device, and in order to maintain the device uniform in operation, the cap —66— is provided with one or more openings —70— leading to the chamber between the dia- 120 phragm and the cap to permit the entrance of air to or the exit of air from said chamber to maintain a normal pressure, irrespective of temperature changes.

These openings may, if desired, be covered 130

on the inside by plate —71—and on the outside by disk —72—for appearance sake so long as sufficient space is provided, as for instance by small grooves or passageways 5 —73—for the escape or entrance of air.

In operation, when the armature shaft is rotated, air entering through inlet —20—is compressed and ejected through outlet —18— into storage chamber —17—, and thence 10 passes thru the hollow horn body —91—to the respective chambers —62—and thence through annular passageways —75—to the interior of the cup-shape member —64— into contact with the front side of diaphragm 15 —68—, whereby diaphragm —68—is caused to move slightly rearwardly to permit the escape of the air through the tube —61—.

The resiliency of the diaphragm and the variation in pressure, due to the escape of 20 air, returns the diaphragm to the position where it closes or substantially closes the inlet to tube —61—and the operation is then repeated, thereby causing a rapid vibration of the diaphragm over the mouth of the tube 25 —62—, producing and causing the projectors to emit a musical tone. The spacing and supporting member —76— may be interposed between the end of the shorter projector —60— and an intermediate portion of 30 the latter, and this spacing and supporting member may be formed with a groove for receiving the edge of the shorter projector and with an inclined surface conforming to the external wall of the longitudinal projector. 35

By adjusting the cup-shape member —64—in the boss —59—a proper positioning of the diaphragm —68— can be effected to produce the desired note, and the member —64— 40 may then be locked in place by lock nut —65—.

From the above it will be apparent that the ornamental sound-emitting portion of the structure including the projectors —60—and 45 the diaphragm chambers and the horn body, are secured to a wall of the vehicle by a single point connection, and are positioned exterior of the vehicle body, while the motor and pump are positioned within the vehicle body, 50 and the entire structure including the horn body —91—and the bracket —104— carrying the motor and pump, rigidly secured in position with respect to the vehicle body by adjusting the nut —102—and altho we have 55 shown and described a specific structure as constituting a preferred embodiment of the invention, we do not desire to restrict ourselves to the details of form, construction or arrangement of the parts, except as the same 60 may be specifically set forth in the claims hereto appended.

We claim:

1. In an apparatus of the class described, 65 the combination with a vehicle body of a combined motor and pump disposed within the

vehicle body, a horn body, diaphragm chamber and projector disposed exterior of the vehicle body, a tubular member connected to the pump and to the horn body, and extending through the vehicle body, and a bracket connected to the combined motor and pump and secured to the vehicle body for supporting the structure. 70

2. In an apparatus of the class described, 75 the combination with a vehicle body of a combined motor and pump disposed within the vehicle body, a horn body, diaphragm chamber and projector disposed exterior of the vehicle body, a tubular member connected to the pump and to the horn body and extending thru the vehicle body, and a bracket connected to the combined motor and pump and secured to the vehicle body and the tubular member for supporting the structure. 80

3. In an apparatus of the class described, 85 the combination with a vehicle body of a combined motor and pump disposed within the vehicle body, a horn body, diaphragm chamber and projector disposed exterior of the vehicle body, a tubular member connected to the pump and to the horn body and extending thru the vehicle body, and a bracket connected to the combined motor and pump, and having an arm resting against the interior of the wall of the vehicle body and 90 having an opening through which the tubular member extends. 95

4. In an apparatus of the class described, 100 the combination with a vehicle body of a combined motor and pump disposed within the vehicle body, a horn body, diaphragm chamber and projector disposed exterior of the vehicle body, a tubular member connected to the pump and to the horn body, and extending through the vehicle body, a bracket connected to the combined motor and pump and having an arm resting against the interior 105 of the wall of the vehicle body and having an opening through which the tubular member extends, and a nut mounted on the tubular member within the vehicle body and adjustable to clamp the bracket and the horn body to the wall of the vehicle body upon opposite sides thereof. 110

5. In an apparatus of the class described, 115 the combination with a vehicle body of a combined motor and pump disposed within the vehicle body, a horn body, diaphragm chamber and projector disposed exterior of the vehicle body, a tubular member connected to the pump and to the horn body and extending through the vehicle body, a bracket connected to the combined motor and pump, and means for clamping the horn body and the bracket to the wall of the vehicle body. 120

6. In an apparatus of the class described, 125 the combination with a vehicle body of a combined motor and pump disposed within the vehicle body, a horn body, diaphragm chamber and projector disposed exterior of 130

the vehicle body, a tubular member connected to the pump and to the horn body and extending through the vehicle body, a bracket connected to the combined motor and pump and

- 5 having an arm resting against the interior of the wall of the vehicle body and having an opening through which the tubular member extends, a nut mounted on the tubular member within the vehicle body and adjustable to clamp the bracket and the horn body
- 10 able to clamp the bracket and the horn body to the wall of the vehicle body upon opposite sides thereof, and means mounted on the tubular member for clamping the bracket and the horn body to opposite sides of the wall of the vehicle body.
- 15

- 7. In an apparatus of the class described, the combination with a vehicle body of a combined motor and pump disposed within the vehicle body, a horn body, diaphragm chamber and projector disposed exterior of the vehicle body, a tubular member connected to the pump and to the horn body, and extending through the vehicle body, a bracket connected to the combined motor and pump and having an arm resting against the interior of the wall of the vehicle body and having an opening through which the tubular member extends, a nut mounted on the tubular member within the vehicle body and adjustable to clamp the bracket and the horn body to the wall of the vehicle body upon opposite sides thereof, and means for securing the bracket to the vehicle body on the inside thereof and for securing the horn body to the wall of the vehicle body on the outside of the latter.
- 20
- 25
- 30

to the wall of the vehicle body upon opposite sides thereof, and unitary means for securing the horn body, the bracket and the wall of the vehicle body together.

8. In an apparatus of the class described, the combination with a vehicle body of a combined motor and pump disposed within the vehicle body, a horn body, diaphragm chamber and projector disposed exterior of the vehicle body, a tubular member connected to the pump and to the horn body, and extending through the vehicle body, a bracket connected to the combined motor and pump and having an arm resting against the interior of the wall of the vehicle body and having an opening through which the tubular member extends, a nut mounted on the tubular member within the vehicle body and adjustable to clamp the bracket and the horn body to the wall of the vehicle body upon opposite sides thereof, and means for securing the bracket to the vehicle body on the inside thereof and for securing the horn body to the wall of the vehicle body on the outside of the latter.

In witness whereof we have hereunto set our hands this 27th day of May, 1927.

GEORGE A. WHITE.
WILLIAM SPARKS.
